UNITED STATES PATENT OFFICE.

FREDERICK SCHWARTZ, OF BROOKLYN, NEW YORK, ASSIGNOR TO ROBERT FINDLAY MANUFACTURING COMPANY, INC., OF BROOKLYN, NEW YORK, A CORPORATION OF NEW YORK.

DESIGN FOR A STAND FOR RADIO LOUD SPEAKERS OR SIMILAR ARTICLES.

Application filed June 20, 1927. Serial No. 22,504. Term of patent 7 years.

To all whom it may concern:

Be it known that I, FREDERICK SCHWARTZ, a citizen of the United States, and a resident of the borough of Brooklyn, city of New York, county of Kings, and State of New York, have invented a new, original, and ornamental Design for a Stand for Radio Loud Speakers or Similar Articles, of which the following is a specification, reference being had to the accompanying drawing, forming a part thereof.

Fig. 1 of said drawing is an elevational view of a stand of my new design, showing a radio loud speaker in dotted lines mounted thereon.

Fig. 2 is a plan view showing the stand top of my new design.

I claim:

The ornamental design for a stand for radio loud speakers or similar articles, as shown.

FREDERICK SCHWARTZ.
